UNITED STATES PATENT OFFICE.

CHARLES WIRT, OF GERMANTOWN, PENNSYLVANIA, ASSIGNOR TO THE
WIRT ELECTRIC COMPANY INCORPORATED, A CORPORATION OF
DELAWARE.

RHEOSTAT.

No. 815,996.

Specification of Letters Patent.

Patented March 27, 1906.

Application filed January 10, 1905. Serial No. 240,391.

To all whom it may concern:

Be it known that I, CHARLES WIRT, a citizen of the United States, residing at Germantown, in the county of Philadelphia and State 5 of Pennsylvania, have invented a new and useful Rheostat, of which the following is a specification.

My invention relates to improvements in rheostats, my object being to provide an improved method of construction whereby a compact fireproof device may be made having the least number of parts and being as free as possible from liability to damage from overheating or the working loose of mechanical fastenings and electrical joints.

My invention especially comprises improved means for introducing a non-conductive supporting mass within a resistance-coil to serve as a form and support therefor.

My invention also comprises various other details in construction and assembling of the different parts.

Referring to the drawings, Figure 1 is a plan view of my device with one-half of the handle and top of the casing removed. Fig. 2 is an elevation of my device with a quarter-section of the coil and case removed on the lines as indicated by *b b* in Fig. 1. Fig. 3 is a view of the mandrel, showing method of winding the coil. Fig. 4 is a plan view of a mold for introducing the supporting material into the coil, a portion of the top thereof being broken away to show the ends of the coil where the material enters. Fig. 5 is a vertical section on lines 5 5 of Fig. 4, the piston shown in elevation.

Similar numerals refer to similar parts throughout the several views.

In Figs. 1 and 2 I show a rheostat in which the resistance 1 is wound in a coil and the coil then bent into an annular shape. The switch 2 is mounted upon a centrally-positioned shaft 3. The outer part of said switch 2 is preferably bifurcated, each branch being composed of a number of laminæ 25, thereby forming brushes to sweep the interior side of the annular coil 1, as is clearly shown in Fig. 2. This switch 2 is clamped to the shaft 3 by the nuts 4, suitable insulations, such as mica washers 5, being interposed between said nuts and switch. Upon shaft 3 is also mounted the handle 19 for the manual operation of the switch. The terminal ring 6, which is electrically connected with one end of the re-

sistance-coil 1, is connected with the binding-post 7. The other terminal ring 8 is electrically connected with the other end of the resistance-coil 1 and is also connected with the binding-post 9. This terminal is also connected by a flexible conductor 10 with the switch 2. When the switch 2 is in direct contact with terminal 8, the entire resistance is in; but when the switch is rotated around to contact with terminal 6 the entire resistance is cut out. Suitable stops (not shown) are provided for limiting the two-way movement of said switch 2—that is, the switch moves in one direction as far as terminal 6 and then encounters a stop, while it is similarly limited in its movement in the other direction when it reaches terminal 8.

The formation of the resistance element is extremely simple and convenient, as follows: The split mandrel 11, as shown in Fig. 3, is secured together by the screws 12 and then mounted in the lathe-centers and the wire wound thereon in the form of a long straight coil. This mandrel is shown as cylindrical, but may of course be oval, square, or of other shape. It is divided longitudinally on a plane oblique to the axis, making two wedge-shaped parts for convenience in withdrawing the mandrel after the coil is wound.

The advantage of winding the resistance-coil complete for a rheostat with one piece of resistance in one operation is very obvious. It effects a great saving in cost. When the straight cylindrical coil has been removed from the mandrel, the terminal rings, such as 6 and 8, are secured to the ends thereof, each terminal ring electrically connected with one terminal of the resistance-wire forming the coil. The coil may then be formed into an annulus and placed in the mold, (shown in Figs. 4 and 5,) this mold being split in two sections 13 and 14, so that the same may be separated to receive the coil, the coil 1 being carefully fitted in one of the annular channels 15 of the mold, so that the two ends of the coil will approach toward the opening of the conducting-channel 16, leaving a space therebetween. When the top half 13 of the mold is fitted over the coil and securely fastened to the other portion 14, a plastic material—such as cement, plaster-of-paris, or the like—is fed into the top of cylinder 17 and forced downwardly by piston 18, through channel 16, into annular channel 15, in and about the

convolutions of coil 1, and filling the entire space therewith. This plastic material should have the property of hardening or of being hardened by some suitable method. 5 When the same has become thoroughly hardened, the coil may be removed from the mold. The said coil 1 and its core now form a firm, compact, and self-supporting body, with the two ends of the resistance-coil electrically connected with terminal rings 6 and 8. A box 20 is now provided, such as is shown in Figs. 1 and 2, around the interior of which is placed a ring 21, of insulating material, such as mica. Upon the top is also 15 placed the mica disk 22. The resistance-ring then being inserted in the case, another mica disk 23 is laid upon it, and the base 24 is forced into place and secured by screws. The resistance element is thus securely held in 20 place and efficiently insulated from the surrounding parts. It is understood, of course, that prior to the placing of the base 24 in position, the switch 2 has also been placed in position, one of the significant features of this 25 construction being that by a simple fitting or proper dimensioning of the various parts the resistance may be secured in place with respect to the associated mechanism simply in the manner above described without anything further than the mere insertion of the 30 binding-post screws 7 and 9 through the casing 20 into the two terminal rings 6 and 8.

While I have shown the coil in the form of a helix, it is obvious that this coil may have 35 any other cross-section, and instead of being bent into an annular shape it may be per-

fectly straight or in other form without departing from the spirit of my invention.

What I claim is—

1. In a rheostat, a removable resistance element composed of a helical coil of wire bent into a circular form and having a core of plastic material which has the property of becoming hard.

2. In a rheostat, a removable resistance element composed of a helical coil of wire bent into a circular form and having a core of plastic material which has the property of becoming hard, and terminals in electrical connection therewith.

3. In a rheostat, the combination of a casing, a removable resistance element composed of a helical coil of wire bent into a circular form and having a core of plastic material, which has the property of becoming hard, and a manually-operated switch adapted to sweep the inner periphery of said resistance element.

4. In a rheostat, the combination of a casing, a removable resistance element adapted to fit said casing and composed of a helical coil of wire bent into a circular form and having a core of plastic material which has the property of becoming hard, terminals secured to said resistance element and binding-posts projecting through the casing into said terminals.

CHARLES WIRT.
